UNITED STATES PATENT OFFICE

GEORGE W. BLAKE, OF WYANDOTTE, MICHIGAN, ASSIGNOR TO GEORGE W. BLAKE MANUFACTURING CO., OF WYANDOTTE, MICHIGAN, A CORPORATION OF MICHIGAN

JOLT PACKING MACHINE

Application filed March 28, 1927. Serial No. 178,964.

The present invention pertains to a novel jolt packing machine constructed for the economical packing of flake caustic, ground caustic, soap chips, bicarbonate of soda, chloride of lime, sugar and other material of kindred nature which does not pack firmly and solidly into a receptacle by merely being poured therein. The machine of this invention jolts the receptacle so that the material deposited therein is packed more tightly than if it were merely allowed to assume its natural condition and density in the container.

The machine comprises essentially a fixed base and a vertically reciprocating top. Movement of the top is obtained by forcing pressure fluid into a cylinder fixed to the base and receiving a piston carried by the top. These positions of the cylinder and piston are not restricted, for the cylinder may be carried by the top and the piston by the base. The flow of pressure fluid to the cylinder is controlled by a reversing valve. Thus, at the end of a stroke which may be regulated in length, the valve is reversed, whereupon the flow of pressure fluid is also reversed and the top proceeds to move in the opposite direction.

Although the principles of the invention may be adopted in various sizes of machines, and the stroke may also be varied indefinitely, a machine for handling containers of fifteen to twenty-four inches in diameter preferably has an adjustable stroke travel of one-half to two inches. A machine of this capacity can pack three to six tons per hour according to the material and the size of the package.

The invention is fully disclosed in the following description and in the accompanying drawings, in which—

Figure 1 is a front elevation of the device, partly in section;

Fig. 2 is an elevation at right angles to Figure 1, partly broken away;

Figs. 3 and 4 are sectional views of two interchangeable thimbles;

Fig. 5 is a vertical section on line 5—5 of Figure 1; and

Fig. 6 is a plan view.

Reference to these views will now be made by use of like characters which are employed to designate corresponding parts throughout.

The device is built upon a base 1 having a number of upright bushings 2 and an open top cylinder 3 fixed thereon by bolts 4 at substantially the center of the base. The machine further includes a top 5 having depending bushings 6 in alignment with the members 2, and these bushings contain guide rods 7 held by pins 8. The guide rods project downwardly beyond the bushings 6 and are slidably received in the bushings 2.

To the lower surface of the top is secured a hollow piston 9 by means of bolts 10. This piston has a sliding fit in the cylinder 3 as shown more clearly in Figure 5.

Near the base is provided a vertical cylindrical valve casing 11 having lateral flanges 12 bolted as at 13 to a flat abutment 14 on the cylinder 3. The valve casing is open at both ends as shown in Figure 5 and receives a valve comprising a stem 15 having two spaced heads 16 and 17. The forward or outermost wall of the casing has an inlet 18, and the rear wall has a right angular duct 19, the longer leg of which is parallel to the axis of the casing 11. The lower end of this leg communicates with another duct 20 formed in the valve casing wall and leading to the bore of the casing. Another duct 21 is formed in the wall of the cylinder 3 in alignment with the duct 20 and in communication with the interior of the cylinder.

The upper end of the stem 15 is formed with a flange or collar 22 on which rests a flanged thimble 23 surrounding the stem and clamped against the collar by a nut 24 threaded on the upper end of the stem. A pair of studs 25 (Figure 1) are formed on the lower surface of the top 5 and support a transverse bar 26 secured thereto by headed bolts 27. This bar has an aperture 28 slidably receiving the body of the thimble 23 which is obviously inserted therein before the nut 24 is applied. The size of the openings 28 is such that the bars cannot pass the flange 22 or the flange of the member 23.

The upper open end of the piston 9 is

normally closed by a flat plug 29 screwed therein. This plug receives in turn a smaller plug 30 having a squared end 31 lodged in an aperture 32 cut through the top 5. This arrangement permits filling the piston with oil and then sealing it. The piston wall has several horizontal passages 33 which convey the lubricant to the engaging walls of the piston and its cylinder. The cylinder wall has a passage 34 formed in a broken line and establishing communication between one of the passages 33 and a duct 35 cut through the valve casing 11 to permit lubrication of the valve heads moving therein.

In the operation of the device, the barrel, drum or other receptacle to be filled is mounted on the top 5 and is secured thereon, if desired, in any suitable manner. During the process of filling, a pressure fluid is forced into the inlet 18. Normally the space between the valve heads 16 and 17 is in communication with the duct 19, and in this position the lower valve head crosses the duct 20 to the interior of the casing. The fluid therefore passes through duct 21 into the cylinder 3 beneath the piston 9 so that the latter is raised. The rising of the top brings the bar 26 into engagement with the flange of the thimble 23 so that the valve is also lifted. When the space between the valve heads passes the duct 19, the flow of the pressure fluid through the valve casing is obstructed; and when the lower head passes the duct 20, the weight on the top 5 forces the pressure fluid in the cylinder out through ducts 21 and 20 and the lower open end of the valve casing 11. When the bar 26 engages the flange 22, the valve is lowered to open position, and the lifting of the piston and top is repeated.

Due to the short distance which the bar 26 may travel before engaging either the flange of the thimble 23 or the flange 22, it will be apparent that the stroke of the piston is comparatively short. The pressure of the fluid forced beneath the piston is sufficient to cause this movement to take place in a short period of time, as a result of which the top receives a jerking movement and jolts the receptacle thereon so that the material fed into the receptacle is packed therein.

The length of the stroke and consequently the effectiveness thereof may be varied by changing the thimble 23. Several such elements of different length are provided, two of which are illustrated in Figures 3 and 4 and designated by the characters 23^a and 23^b. Since the lower blank end of the thimble rests on the flange 22, the length of the thimble varies the distance between its flange and the top of the bar 26, whereby the length of the piston stroke is varied accordingly. Changing the thimble is equivalent to adjusting the flange thereof lengthwise of the valve stem 15. The particular valve shown

is merely illustrative of any valve capable of reversing the flow of pressure fluid with reference to a cylinder, and may be designated as a reversing or reversible valve.

The base 1 carries a pair of upright yokes 36 which slidably receive stems 37 depending from the top 5. Each stem is surrounded by a spring 38 having its upper end bearing against the top of the yoke and its lower end bearing against a disk 39 held on the stem by lock nuts 40. This arrangement prevents the top from being thrown off the base by the momentum of its upward stroke. Further, the compression of the spring on the upward movement of the base limits and cushions the upward stroke. The downward stroke is cushioned by the compression of fluid in the cylinder 3, since this fluid is exhausted through the comparatively small ducts 21 and 20.

Although a specific embodiment of the invention has been illustrated and described, it will be understood that various alterations in the details of construction may be made without departing from the spirit of the invention as indicated by the appended claims.

What I claim is:—

1. A packing machine comprising a base, a top mounted over said base, a co-operating cylinder and piston carried by said base and top respectively, means for admitting pressure fluid to and the exhaust of fluid from said cylinder including a reversing valve having a stem, a thimble detachably mounted on said stem, and a member carried by said top to engage the thimble, said thimble being of greater length than the thickness of said member to provide lost motion between said member and stem, whereby said valve is moved with a short quick movement at the ends of the stroke of said piston and the length of such stroke may be adjusted by substituting thimbles of different lengths.

2. A jolt packing machine comprising a base, a top mounted upon said base in spaced relation thereto, guides for said top, means for vertically reciprocating said top, yokes fixed to the base, springs within said yokes, and stems fixed at their upper ends to said top and passing through said yokes and springs with their lower ends engaging the lower ends of said springs to resist upward movement of the top.

3. A jolt packing machine comprising a base, a vertically movable top above said base and spaced therefrom, a cylinder on the base positioned centrally thereof, a hollow piston secured to said top to engage within said cylinder, a piston valve to control the admission of fluid pressure to and the exhaust of fluid from said cylinder, and means carried by said top for operating said valve, said cylinder and piston being provided with oil passages for conducting oil from said hollow piston to said piston valve.

4. A jolt packing machine comprising a base, a top above and spaced from said base, co-operating guides on said base and top to guide said top in its vertical movement, a cylinder on the base located centrally thereof between said base and top, a hollow piston depending from said top to engage within said cylinder, said hollow piston forming an oil chamber having a fill opening open through said top, a closure for said fill opening, a slide valve for controlling the admission of fluid to and the exhaust of fluid from said cylinder, means operated by said top for operating said valve, said piston and cylinder being formed with co-operating passages for conducting oil from said oil chamber to said valve, yokes secured to said base beneath said top, stems secured to said top and extending downwardly through said yokes, and springs sleeved upon said stems within said yokes to resist upward movement of said top.

In testimony whereof I affix my signature.
GEORGE W. BLAKE.
